UNITED STATES PATENT OFFICE.

HERMAN BETKE, OF DENVER, COLORADO.

STEAM BOARD.

Application filed May 20, 1926. Serial No. 110,425.

This invention relates to apparatus of a class commonly known as steam boards employed generally for the steaming of fabrics to eliminate wrinkles, raise the nap of said 5 fabrics and the like, and has reference more particularly to apparatus commonly known as a steam sleeve boards; an object of the invention being to provide an improved construction for machines of the above class 10 wherein means are provided for heating the machine prior to the admission of the operating steam in order to prevent condensation of said steam through contact with cold parts of said machine during operation thereof. 15 A further object of the invention is to be found in the provision of means for trapping and removing water of condensation which may collect in said machine.

My invention consists in the construction, 20 arrangement and combination of elements hereinafter set forth, pointed out in my claims and illustrated by the accompanying drawing, in which—

Figure 1 is an elevation of my improved 25 device assembled and ready for use. Figure 2 is a cross section on an enlarged scale on the indicated line 2—2 of Figure 1. Figure 3 is a longitudinal section on an enlarged scale on the indicated line 3—3 of Figure 2. Figure 4 is a vertical section of a modified 30 form of my invention. Figure 5 is a cross section on an enlarged scale on the indicated line 5—5 of Figure 4. Figure 6 is a vertical section of another modified construction of 35 my invention. Figure 7 is a cross section on an enlarged scale on the indicated line 7—7 of Figure 6. Figure 8 is a fragmentary vertical section of a portion of the head and standard shown in Figure 1.

In the construction of my device as shown, 40 the numeral 10 designates generally a steam or working head, substantially cylindrical in form, closed at its ends and preferably formed of a suitable metal by moulding or casting. A chamber 11 is formed within 45 said head 10, longitudinally thereof and extends the length of said head between the closed ends thereof; said chamber being eccentric of said head in such manner as to provide a greater thickness in the upper 50 wall of said head than in the lower wall. Parallel, longitudinal bores 12, in this instance three in number, are formed in the upper, thicker wall of the head 10, above 55 and parallel with the chamber 11, said bores being closed at one end adjacent the end of

said head and converging at the other end to unite in a common neck 13 extending through the end of the head 10. Spaced holes or vents 14 are formed in the upper 60 wall of the head 10 and communicate through said wall with the bores 12 throughout the length of said bores. A boss 15 is formed on the lower side of the head 10, adjacent one end of said head; said boss being formed with a bore communicating with the chamber 11, said bore being internally screw-threaded and adapted to receive the threaded end of a support or pedestal 16. The support 16 may be of any form or construction desired, the particular form illustrated, comprising a tubular stem portion threaded at its upper end and divided near its lower end to form bracing leg portions provided with flanges adapted to be secured 70 to a floor or the like, being but one of many suitable constructions. A chamber 17 is formed in the upper end of the support 16 and is open at its upper end communicating through the bore in the boss 15 with the chamber 11 of the head 10. A steam pipe or line 18 leads from a source of steam (not shown), the threaded end of said line being received by the internally threaded end portion of the neck 13, said line being provided with a valve 19 adjacent the head 10, whereby the flow of steam through said line may be controlled. A branch line 20 is connected to the steam line 18 between the source of steam and the valve 19, said branch passing 80 through a threaded hole in one end of the head 10 and extending longitudinally the length of the chamber 11, within said chamber, and terminating in an open end adjacent and slightly spaced from the other end 85 of said head. A pipe 21 is tapped into the support 16 in communication with the bottom of the chamber 17 and leads through a control valve 22 to any suitable place for the discharge of exhaust steam and water. 90

In the modified construction shown in Figures 4 and 5, an elbow 15' is formed with a threaded bore adapted to receive and engage the threaded end of the support 16 and a stepped bore at right angles to said first bore and communicating therewith. A cylinder 10', closed at one end and provided with external threads adjacent its open end is formed of sheet metal or the like with perforations 14' in the top portion of its curved surface and is adapted for threaded engagement with the larger of the bores in 100 105 110

the elbow 15'. A second cylinder 11', closed at one end and provided with external threads adjacent its open end is adapted for threaded engagement with the lesser of the 5 bores in the elbow 15' and is thereby positioned within and spaced from the cylinder 10'. The steam line 18, in this construction, connects with the space between the cylinders 10' and 11' through the valve 19 and 0 the elbow 15' and the branch line 20 extends through the elbow 15' within and nearly to the closed end of the cylinder 11'. The pipe 21 is branched in this construction, one branch communicating with the bottom 5 of the chamber 17 and the other branch passing through the elbow 15' to communicate with the open end of the cylinder 11' near the bottom of said cylinder, each branch being provided with a control valve 22.

20 In the construction shown in Figures 6 and 7, a cylinder 11" is formed with an internally threaded boss to receive the threaded end of the support 16, said cylinder being hollow, closed at both ends and
25 provided with diametrically opposite, downwardly extending ears longitudinally of its curved surface. A semi-circular steam chamber 10" is formed of sheet metal, is provided with closed ends and perforations
30 on its upper convex surface and is formed with marginal flanges adapted to engage beneath the ears of the cylinder 11" and position the steam chamber 10" on and in contact with said cylinder. In this construction the steam line 18 communicates through the valve 19 with one end of the chamber 10" and the branch 20 passes through one end of the cylinder 11" and terminates in an open end adjacent the
35 other end of said cylinder; the pipe 21 and valve 22 being the same as first described.
40

In the operation of my device, the valve 22 is first opened, whereupon steam is admitted to the chamber 11 through the branch line 20, said steam being discharged into said chamber at the end most removed from the outlet, whence it circulates back through said chamber, heating the head 10 and vaporizing any water which may have collected in the tubes or bores 12, and passes out through the chamber 17, pipe 21, and valve 22 together with any water of condensation which may have collected in the chambers 11 and 17. When the operating head has become thoroughly heated, the valve 22 may be closed and the machine is then ready to be used. Opening of the valve 19 will permit steam to pass into the bores 12 whence it will escape under pressure through the vents 14 through fabrics which are placed over said vents on the head 10. The operation of the two modified

constructions shown is the same as above recited, save that, as shown in Figure 4, provision is made for draining the cylinder 10' through the chamber 17 while the cylinder 11' is drained by a branch of the pipe 21. It is obvious that in this latter construction the lower of the two valves 22 must be closed when the valve 19 is opened for the steaming of fabrics. 65 70

It is easily apparent that slight mechanical changes of my construction may be made without departing from the spirit and principle of my invention, hence I do not wish to be understood as being limited to the specific construction and arrangement illustrated and described, but rather by the scope of the appended claims. 75

I claim as my invention—

1. A steam board comprising a standard adapted to be secured to a base, a substantially cylindrical head secured at one end to the upper end of said standard and projecting laterally therefrom, means within said head adapted for connection with a source of steam whereby steam may be discharged through vents in the convex upper surface of said head, said means comprising spaced parallel bores closed at one end and converging to form a common chamber at the other end, separate means within said head adapted to be connected with a source of steam whereby said head may be heated by the circulation of steam through said latter means, together with means carried by said standard and coacting with said latter means carried by said head for exhausting steam and water of condensation from said head.

2. In a device of the character described, a standard adapted to be secured to a base and formed with an upwardly opening

Signed at Denver, in the county of Denver
and State of Colorado, this 14th day of
May 1926.
